UNITED STATES PATENT OFFICE.

FRANK L. WHITE, OF LITTLE ROCK, ARKANSAS, ASSIGNOR OF THREE-TENTHS TO
ROBERT W. GRIFFITH, OF LITTLE ROCK, ARKANSAS, AND THREE-TENTHS TO
ROBERT B. SUTTON, OF WINONA, MISSISSIPPI.

BALING-PRESS.

1,018,284.

Specification of Letters Patent. Patented Feb. 20, 1912.

Application filed June 18, 1910, Serial No. 567,729. Renewed May 23, 1911. Serial No. 629,061.

To all whom it may concern:

Be it known that I, FRANK L. WHITE, a citizen of the United States, residing at Little Rock, in the county of Pulaski and 5 State of Arkansas, have invented certain new and useful Improvements in Baling-Presses, of which the following is a specification.

My invention relates to an improvement 10 in baling presses in which a movable platen is operated by any suitable actuating means.

The object of the invention is to provide a compound toggle by which I am enabled to obtain a greater leverage in raising 15 the movable platen, and by which connection, the cost of operating the press is materially reduced.

The invention consists in certain novel 20 features of construction and combinations of parts which will be hereinafter fully described and pointed out in the claims.

In the accompanying drawings:—Figure 1 is a view in side elevation; Fig. 2 is a similar view, partly in section, to disclose 25 the inner assemblage of parts; Fig. 3 is a perspective view of one of the levers; Fig. 4 is a perspective view of one of the arms; and Fig. 5 is a perspective view of the levers.

30 A represents the base, and 1, 1, are the uprights, to which a cross-beam B is connected at the upper ends thereof. Connected to the under side of the cross-beam is the upper platen D. The lower platen 35 C is provided with recesses 2, 2, in which are journaled arms 3, 3. The outer ends of these arms are provided with rounded portions 4, and between these portions grooves 5 are formed. Levers 6 are journaled in 40 bearings 7, which bearings are connected to the base A, and the upper surfaces of the levers are provided with rounded teeth 8, and between the teeth grooves 9 are formed, in which are received the rounded 45 teeth or portions 4 of the arms 3, the interlocking of the teeth of the arms 3 and levers 6 producing a knuckle joint or connection. Slotted guide-plates 10, connected to the levers 6, extend upwardly, and extending 50 through the curved slots 11 in the plates are pins 12, which pins are connected to the arms 3, these guide-plates insuring the proper meshing of the teeth of the arms and levers.

Standards 13 are mounted upon the base 55 A, on each side of the press, and journaled in the standards are crank shafts 14', to which are connected arms 14, 14. Pivotedly connected to the upper ends of the levers 6 are links 15, which links are connected 60 to the crank arms 14. Mounted upon each shaft 14' is a gear wheel 16. The gear wheels 16 are adapted to mesh with each other. A shaft 17 is journaled in the standards, and mounted upon the shaft is a pinion 18 which meshes with one of the gear wheels 16. A pulley wheel 19 is mounted upon the shaft 17, which is adapted to be driven from any suitable source of power 65 for operating the shaft 17, causing the gear 70 wheels 16 to be operated.

Upon the rotation of the shaft 17, which causes the pinion 18 to be moved whereby the gear wheels 16 are rotated, the links 15 will be drawn inward toward each other, 75 causing the levers 6 to be raised. The upward movement of the levers 6 causes the arms 3 to move upwardly, which forces the lower platen C upward. The toothed faces of the arms 3 and levers 6 have a free engagement with each other, forming a bearing to allow of a rocking action. By reversing the pulley wheel 19, the platen C can then be lowered.

Having fully described my invention, 80 what I claim as new and desire to secure by Letters Patent, is:—

1. In a baling press, the combination with a frame, of upper and lower platens, arms connected to the lower platen, levers connected to the frame, the faces of the arms and levers in free engagement with each other, forming a bearing to permit of a 90 rocking action, and means connected to the levers for raising the platen. 95

2. In a baling press, the combination with a frame, of upper and lower platens, arms connected to the lower platen, levers connected to the frame, teeth on the arms and levers meshing to form a bearing, and means 100 connected to the levers for raising the platen.

3. In a baling press, the combination with a frame, of upper and lower platens, arms connected to the lower platen, levers pivotedly connected to the frame, the faces of the arms and levers in engagement with each other, forming a bearing to permit of a 105 a

rocking action, crank shafts mounted on the frame, means connecting the levers to the crank shafts, gear wheels mounted on the crank shafts, and means for operating the 5 gear wheels for actuating the arms and levers, whereby the platen is moved.

4. In a baling press, the combination with a frame, of platens, arms connected to one of the platens, levers connected to the frame, 10 teeth on the arms and levers meshing for forming a bearing, links connected to the levers, and means engaging the levers for moving the platen.

5. In a baling press, the combination with

a frame, of platens, arms connected to one 15 of the platens, levers connected to the frame, teeth on the arms and levers meshing, links connected to the levers, crank shafts on the frame connected to the links, and means for operating the crank shafts for moving the 20 platen.

In testimony whereof I affix my signature, in the presence of two witnesses.

FRANK L. WHITE.
